UNITED STATES PATENT OFFICE.

CHARLES P. BYNON AND JAMES STEWART, JR., OF YONKERS, NEW YORK.

LAMP ATTACHMENT.

SPECIFICATION forming part of Letters Patent No. 312,810, dated February 24, 1885.

Application filed July 1, 1884. (No model.)

To all whom it may concern:

Be it known that we, CHARLES P. BYNON and JAMES STEWART, Jr., of Yonkers, in the county of Westchester and State of New York, have invented a new and Improved Lamp Attachment, of which the following is a full, clear, and exact description.

This invention has for its object to provide a cheap and convenient device to be attached to lamps for holding the lamp-burner, or burner and globe combined, thus obviating the necessity of removing the burner and wick from the lamp while the lamp is being filled.

Reference is to be had to the accompanying drawings, forming a part of this specification, in which similar letters of reference indicate corresponding parts in all the figures.

Figure 1 is a perspective view of our invention. Fig. 2 shows the device attached to the lamp for use. Fig. 3 is a plan view of a lamp-collar provided with a stud for holding the attachment in position for use. Fig. 4 is a similar view of a clasp-ring for holding the attachment, the ring being adapted to be applied to lamps already in use; and Fig. 5 is a perspective view of a modification.

A represents the attachment. This in most cases will be made in two parts—the main part A' and the bow A². The part A' is bent to form the arm a, downwardly-projecting fold b, and lip c. The bow A² is riveted to the outer end of the arm a, as shown clearly in Fig. 1, and the arm a is formed with the retaining-notch d, to receive the wick-spindle w of the burner T of the lamp U, as shown in Fig. 2. For lamps already in use, to apply the attachment A for holding the burner T, it is only necessary to slip the lip c over the edge of the collar V of the lamp after the burner has been unscrewed, when the lip c and fold b will act against the collar V and hold the arm a out in horizontal position, so that by simply placing the spindle w in the slot d and the burner upon the bow A² the burner will be held away from the lamp, as shown in Fig. 2, so as not to interfere with the filling of the lamp.

In some cases for lamps already in use we shall provide the ring B, (shown in Fig. 4,) which is a split ring made, preferably, of 50 spring metal and formed with the T-stud e and loop f, either or both, to hold the lip c, the ring being adapted to be placed around the collar V of the lamp. For use with the T-stud e the lip c must be slotted to form the claws c' c', as 55 shown in Fig. 1. These claws are not necessary with the loop f, nor when the attachment is applied directly to the collar V.

When new burners are made to receive our new attachment, the collar V will have formed 60 upon it or secured to it the T-stud g, or similar fixed device, as shown in Fig. 3, to receive and hold the lip c, or the claws thereof, and when the attachment is made to be used especially with the studs e g or loop f the fold 65 b may be omitted, if desired.

Instead of riveting the bow A² to the arm A', the bow and arm may be made in one solid piece stamped from sheet metal, if desired, as 70 shown in Fig. 5.

Having thus described our invention, we claim as new and desire to secure by Letters Patent—

1. As an improved article of manufacture, a lamp attachment consisting of a bar having 75 a lip at one end for securing it to a lamp and a burner-support at its other end, as set forth.

2. The attachment A, composed of the slotted arm a, lip c, and bow A², substantially as described.

3. The attachment A, composed of the arm a, fold b, lip c, and bow A², substantially as described.

4. The attachment A, formed with the claws c', in combination with a stud formed upon or 85 attached to the collar of the lamp, substantially as and for the purposes set forth.

CHARLES P. BYNON.
JAMES STEWART, JR.
